(57) **CLAIM**

I claim the ornamental design for a toothbrush with clip attachment, as shown and described.

DESCRIPTION

FIG. 1 is a front perspective view from above and one side; FIG. 2 is an exploded perspective view showing the clip attachment separated from the toothbrush;

FIG. 3 is a front view;

FIG. 4 is a rear view;

FIG. 5 is a view from the other side;

FIG. 6 is a plan view; and,

FIG. 7 is an underneath plan view.
